Primary Examiner—Celia A Murphy(74) *Attorney, Agent, or Firm*—Klarquist Sparkman, LLP**(57) CLAIM**

I claim the ornamental design for a golf shoe outsole, as shown and described.

DESCRIPTION

FIG. 1 is a right side elevational view of a golf shoe outsole showing my new design;

FIG. 2 is a bottom plan view thereof;

FIG. 3 is a left side elevational view thereof;

FIG. 4 is a rear elevational view thereof;

FIG. 5 is a front elevational thereof;

FIG. 6 is a top plan view thereof; and,

FIG. 7 is a perspective view of the golf shoe outsole of FIG. 1. The dashed lines in the drawings are for illustrative purpose only and form no part of the claimed design.
